UNITED STATES PATENT OFFICE.

JOHN S. BETTIS, OF HANOVER, NEW YORK.

IMPROVEMENT IN FARM-FENCES.

Specification forming part of Letters Patent No. 57,073, dated August 14, 1866.

To all whom it may concern:

Be it known that I, JOHN S. BETTIS, of the town of Hanover, in the county of Chautauqua and State of New York, have invented an Improvement in Farm-Fences; and I do hereby declare that the following is a full and exact description thereof, reference being had to the accompanying drawings, making a part of this specification, in which—

Figure I is a perspective view, showing a section of the fence as built. Fig. II is a top-edge view, showing the beveled and lapping ends of the boards or rails. Fig. III is also a top-edge view, showing the manner of inserting a wedge between the beveled and lapping ends of the boards or rails. Fig. IV is an elevation of an iron post supported in a foundation-stone, with the hooks or staples connected therewith, showing the construction of the hooks or staples and the manner of fastening them to the posts.

The nature of this invention consists, first, in the construction and use of a hook or staple for holding the boards or rails, having a single or double loop, which clasps the post and is made fast thereto; second, in the construction and use of a staple or hook having a single or double loop which slides over the post, and is made adjustable thereon and fastened thereto by means of a key or wedge.

Letters of like name and kind refer to like parts in each of the figures.

A represents a round iron post of any required length and three-quarters of an inch (more or less) in diameter. It is fastened to a bowlder, rock, or stone, B, in a common and well-known manner, and the bowlder, rock, or stone is set in the earth as a foundation in a common manner.

An embankment may or may not be, as preferred, raised along the line of the fence.

C represents an iron hook or staple, which is devised as a cheap and effective means of holding and supporting the boards or rails of the fence. It has a single loop, as shown most clearly at c', Fig. IV, or a double loop, as shown

at c² c², Fig. IV, which loops clasp and slide over the post, and are made fast to the post at any point required by means of the wedge or key d. This construction gives a secure connection of the hooks to the posts and makes them adjustable thereon.

The wedge may be driven whenever it is required to remove the hooks or change their position on the posts. If in any case it may be desirable to attach the hooks permanently to the post, dispensing with the adjustable feature, they may be put on hot, or, as is known among mechanics, "shrunk on."

E represents narrow boards or rails of any required length, used for the purpose of making the fence. These are beveled at their lapping ends, as shown in Figs. II and III, and are intended to fill (or nearly fill) the space between the hook and post. In case they do not fit sufficiently tight in the hook a wooden wedge may be driven in, as shown at f, Fig. III.

Extra single loop-hooks are used on a post wherever it is desirable to change the direction of the fence, as shown at g, Fig. I.

Narrow boards, split rails, or round poles may be used in connection with these hooks, and hence it is evident that a very cheap and a very strong fence may be made upon the principle of this improvement, and the improvement will render available either of the said materials for rails in any part of the country where either is most abundant.

What I claim as my invention, and desire to secure by Letters Patent, is—

1. The hook C, as a means of holding and connecting the rails and post, made either with a single or double loop, substantially as herein described.

2. The hook or staple C, with a single or double loop, made adjustable on the post by means of the key or wedge d, substantially as set forth.

JOHN S. BETTIS.
